United States Patent Office.

HENRY A. ALDEN, OF FISHKILL, NEW YORK, ASSIGNOR TO NEW YORK RUBBER COMPANY.

Letters Patent No. 71,942, dated December 10, 1867.

IMPROVEMENT IN INFLATING RUBBER BALLS.

The Schedule referred to in these Letters Patent and making part of the same.

TO WHOM IT MAY CONCERN:

Be it known that I, HENRY A. ALDEN, of Fishkill, in the county of Dutchess, and State of New York, have invented certain new and useful Improvements in the Method and Means for Inflating Hollow Rubber Balls and other like articles; and I hereby declare the following to be a full, clear, and exact description of the same, reference being had to the accompanying drawings, in which—

Figure 1 represents a vertical section of a rubber ball to which my improvements are applied, the section being taken through the inflating-bulb and tube.

Figure 2 represents an elevation of the same, with the tube and bulb drawn out or projecting from the ball.

It has been found requisite, both in order to transport rubber balls and other like hollow articles, cheaply and with safety in bulk, and to keep such articles properly distended or inflated at all times when in use, that they should be constructed or made so as to admit of the air being either forced and confined within them, or discharged from them, according as it is desired to maintain them in a distended or in a collapsed condition. My invention consists in certain improved means for effecting this result, and will be best understood by reference to the drawings which accompany this specification.

A is a hollow rubber ball, which, while of otherwise ordinary or suitable construction, has formed in it, at any desired point, an orifice or hole, *a*, in which is secured the bulb *b* and the tube *c*, by which the latter is surmounted. The form of the bulb and tube, which are made or moulded in one piece of vulcanized rubber, is shown plainly in fig. 2, where they are represented as drawn out from the orifice *a* in the ball. The device is attached to the ball in the manner shown in the drawings, and by any suitable means. The bulb *b* is turned inside out, so as to form a cup, in which the tube *c* is received, and the end of said bulb is united with the inner face of the ball, immediately surrounding the orifice *a*. This position of the parts is shown plainly in black lines in fig. 1. The length of the tube *c* is such that when in this position its outer end will be flush with the exterior surface of the ball. When the ball is in the collapsed condition shown in red lines, fig. 1, and it is required to inflate it, the tube *c* is drawn out until it occupies the position shown in fig. 2, and in red lines, fig. 1. By this operation the tube is not only drawn out from the bulb, but the latter is drawn out from the ball, and the two project from the orifice *a* in the manner shown in the drawings referred to. Air is now blown through the tube into the ball, and as soon as the requisite quantity has been forced in to properly inflate the ball, the bulb or tube is compressed between the thumb and finger, so as to prevent the escape of the air, until a plug or stopper, *d*, of hard rubber or other suitable material, can be inserted in the open end of the tube. As soon as this is done, the bulb and tube are caused to return to their positions within the orifice *a*, by pressing down upon the tube; for thereby the bulb will commence to yield or be depressed at the shoulder *x*, where it joins the tube, and will gradually be forced down within the orifice, until it springs back to the position shown in dark lines, fig. 1, the end of the tube *c* being about flush with the exterior of the ball.

The bulb, when in either of the positions shown in the drawings, will hold the tube firmly in such position, on account of the well-known springiness such bulbs possess when pressed in one direction or the other beyond a certain distance. When it is required to discharge the air from the ball, this can be accomplished by simply removing the plug *d* from the tube, as will be readily understood without explanation.

The combined tube and bulb may be attached to or united with the ball by suitable means, and in other ways than herein described, as will be readily understood by those skilled in the art to which this invention pertains, and the device is, of course, applicable not only to rubber balls, but to any other hollow articles, such as pessaries, &c., which are of such nature as to be capable of being distended by inflation.

Having now described my invention, and the manner in which the same is or may be carried into effect, what I claim, and desire to secure by Letters Patent, is—

The application to rubber balls or other hollow articles, requiring to be distended by inflation, of the combined bulb and tube, substantially in the manner and for the purposes herein shown and set forth.

In testimony whereof, I have signed my name to this specification before two subscribing witnesses.

H. A. ALDEN.
